UNITED STATES PATENT OFFICE

WALTER W. WILLIAMS, OF BLOOMINGTON, ILLINOIS, ASSIGNOR TO WILLIAMS OIL-O-MATIC HEATING CORPORATION, OF BLOOMINGTON, ILLINOIS, A CORPORATION OF ILLINOIS

ELECTRICALLY OPERATED REFRIGERATING MECHANISM

Application filed January 2, 1930. Serial No. 417,905.

This invention relates to improvements in electrically operated refrigerating mechanism and more particularly to that type in which the refrigerant in gaseous form is compressed, condensed to a liquid, and in liquid form delivered to an evaporator within the ice box or cabinet and after changing therein from liquid to gaseous form returned as a gas to the compressor.

It is an object of this invention to provide a compressor and condenser which will form a unit that may be either located within the compartment usually formed for the operating mechanism in cabinets constructed for electrically operated refrigeration, exteriorly of the cabinet or even exteriorly of the room in which the cabinet is located and from the desired location the compressor and condenser unit may be connected with the evaporator within the cabinet in any desired manner, such as, that shown and described in my prior copending application Serial No. 406,234, filed November 11, 1929. It is a further object of this invention to provide a unit of the character described which compact, of simple construction and efficient in performing its functions.

With these and other objects in view reference is made to the accompanying sheet of drawings which illustrate a preferred form of this invention with the understanding that minor detail changes may be made without departing from the scope thereof.

In the drawings:

Figure 1 is a view in side elevation of an embodiment of this invention.

Figure 2 is a bottom plan view of Figure 2, with the bottom plate removed.

Figure 3 is a detail fragmentary view, partly in side elevation and partly in section taken on the line 3—3, Figure 2.

Since this invention relates only to the construction and arrangement of the compressor and condenser in a single unit that may be connected with any type of evaporator in an electrically operated device of this character employing a gaseous refrigerant, it is not deemed necessary to illustrate the other parts.

The compressor and electric motor for op-

erating the compressor are enclosed within a dome 1 hermetically sealed upon a closed casing 2 to which the gaseous refrigerant is returned from the evaporator, compressed by the compressor therein and the compressed gaseous refrigerant delivered to a condenser 3. The casing 2 and dome 1 mount therein an electrically operated compressor in the manner shown and described in my said prior copending application Serial No. 406,234. The casing 2 is preferably circular in form and is mounted above and spaced apart from a similarly shaped base plate 4 by a perforated tubular support 5. The condenser 3 comprises a coil of pipe having a plurality of turns concentric with the vertical center line of the casing 2 and support 5 which are arranged in spaced relation adjacent to the said support 5 with the uppermost coil connected to the discharge side of the compressor and the lowermost coil connected to a liquid receptacle 6, preferably arranged thereunder in the form of an arcuate tube, as shown in Figure 2, with a connection for a pipe leading to the high side of an evaporator.

Within the perforated tubular support 5 and coils of the condenser a circulating fan 7 is mounted on an electrically operated motor shaft preferably aligned with the vertical center line of the support 5 and casing 2, the motor 8 for the fan 7 being supported as shown and may be connected in series with the compressor motor circuit, if desired, so that the compressor and fan will act in unison. A circular baffle 9 is arranged intermediate the coils of the condenser 3, as shown.

The operation of the fan 7 sets up a circulation of air from the surrounding atmosphere drawing it in through the perforation of the support 5 and lower coils of the condenser 3 below the baffle 9 and expelling it through the upper coils of the condenser above the baffle 9, as indicated by the arrows, to cool the contents thereof. The outgoing air passing through the upper coils, the uppermost of which is connected to the compressor, acts upon the coils of greatest heat, reducing the temperature so that the incoming air completes the cooling in the

lower coils without appreciably increasing the temperature of the air passing therethrough.

The mobility of the unit is the same as 5 that referred to in my said prior copending application and this construction and arrangement has the further advantage of possessing a positive mechanical means for circulating the atmospheric air about the condenser in a most efficient manner.

What I claim is:

1. In an electrically operated refrigeration device, a unit compressor and condenser including a compressor casing, and a condenser 15 mounted thereunder comprising a plurality of coils having the uppermost coil connected to the discharge side of the compressor, and means surrounded by the condenser for withdrawing atmospheric air 20 through the lower coils thereof and expelling such air through the upper coils.

2. In an electrically operated refrigeration device, a unit compressor and condenser including a compressor casing and a condenser 25 mounted thereunder comprising a plurality of coils having the uppermost coil connected to the discharge side of the compressor and a circulating fan mounted below the compressor casing adapted to circulate 30 atmospheric air about the condenser coils.

3. In an electrically operated refrigeration device, a condenser including a plurality of helical coils, a perforated tubular support 35 surrounding said coils, a compressor mounted upon said support above said coils, the upper end of the helical coil connected to the discharge side of the compressor, an arcuate tubular liquid receptacle arranged 40 within said support below the said coils, the lower end of the helical coil connected to said receptacle, a circulating fan mounted within said support and helical condenser coil adapted to draw air within the support 45 through the lower perforations and condenser coils and discharge said air through the upper condenser coils and perforations.

4. In an electrically operated refrigeration device, a condenser including a plurality 50 of helical coils, a perforated tubular support surrounding said coils, a compressor mounted upon said support above said coils, the upper end of the helical coil connected to the discharge side of the compressor, a baffle extending 55 intermediate the coils of the condenser, an arcuate tubular liquid receptacle arranged within said support below the said coils, the lower end of the helical coil connected to said receptacle, a circulating fan 60 mounted within said support and helical condenser coil adapted to draw air within the support through the lower perforations and condenser coils below said baffle and discharge 65 said air through the upper condenser coils and perforations above said baffle, and

means for operating the circulating fan in unison with the compressor.

5. In an electrically operated refrigeration device, a unit compressor and condenser including a compressor casing, and a condenser 70 mounted thereunder comprising a plurality of coils connected to the discharge side of the compressor, and means surrounded by the condenser for withdrawing atmospheric air through the lower coils thereof and expelling such air through the upper coils.

6. In an electrically operated refrigeration device, a condenser including a plurality of helical coils, a perforated tubular support 80 surrounding said coils, a compressor mounted upon said support above said coils, and end of the helical coils connected to the discharge side of the compressor, an arcuate tubular liquid receptacle arranged within said support, the other end of the helical coil connected to said receptacle, a circulating fan mounted within said support and helical condenser coil adapted to draw air within the support through the lower perforations and condenser coils and discharge said air through 85 the upper condenser coils and perforations
